UNITED STATES PATENT OFFICE

ARTHUR SPRENGER, OF BERLIN-CHARLOTTEBURG, GERMANY, ASSIGNOR TO
FRIEDRICH SIEMENS AKTIEN GESELLSCHAFT, OF BERLIN, GERMANY

REHEATING FURNACE

Application filed February 20, 1929, Serial No. 341,414, and in Germany December 11, 1928.

Modern rolling mill practice imposes ever increasing demands on the average output capacity of reheating furnaces for ingots, a requirement which, however, with the furnace constructions now in use can only be used by increasing the number of furnaces. This expedient can in most cases not be adopted, owing to lack of space. For the same reason the otherwise obvious expedient of increasing the length of the reheating furnaces finds a limit which cannot be exceeded. According to this invention a solution of the problem of increasing the output of reheating furnaces is found without increasing the space required.

The gradual, uniformly increasing heating of the ingots is effected by a flame sweeping through the furnace from the discharging end to the charging end in a uniform direction, the ingots travelling through the furnace in opposition to the direction of the flame. For producing this single-direction flame burners of any form which are fed directly with coke-oven gas, producer gas or the like may be used. With such an arrangement a definite rather low limit for the length of the oven may not be exceeded, as the flame streaming into the furnace from the burners first comes in contact at the discharge end with the most highly preheated ingots and must not heat these too fiercely, as there is otherwise the danger of too great a loss of material through burning.

A far more economical manner of working such reheating furnaces can be effected by using a regenerative method of heating, in which a portion of the reversible regenerative flame is branched off, which sweeps through the furnace right to the charging end without changing its direction. For obtaining its full effect this flame of course requires a certain length of furnace. This length may, however, not be exceeded and it has therefore already been proposed to provide, starting from the discharging end of the

furnace, several burners one behind the other in the furnace arch or in the side walls of the furnace, through which portions of the entire furnace flame or additional flames are introduced into the furnace. In this way the length of the furnace may be increased, it is true, and thereby an increase be obtained in the furnace output, but this increase in the length of the furnace extends substantially to the hottest part of the furnace, formerly called the welding hearth, so that there is the danger of an increased amount of waste. Furthermore it is not possible in this way to obtain in the hottest part of the furnace (the welding hearth) a uniform increase in temperature, as with a single flame, since at each of the burners arranged one behind the other the flame there entering forms a certain maximum, so that the course of the temperature curve of the oven towards the discharging end would not be regular, but undulating.

It has also been proposed to divide the reheating furnace, say by a partition or in some other way, into the so-called welding hearth and the bundle or preheating hearth and to provide each of these hearths with separate regenerative firing. This furnace construction, however, also has considerable disadvantages. In the first place the accessibility of the furnace is considerably interfered with by the necessary lateral arrangement of the regenerative firing for the bundle, while on the other hand the ingots which have been highly preheated in the bundle by the separate regenerative firing pass to the welding hearth at a too high temperature, so that there must be considerable wastage in this part of the furnace or, if this disadvantage is to be avoided, there will be a break, at the place where the bundle merges into the welding hearth, in the uniform increase in temperature which must also be regarded as undesirable.

The desired increase in the output of re-

- heating furnaces is realized according to the present invention, while the disadvantages attaching to the hitherto known constructions of such furnaces are avoided both as
- 6 **6** regards the lateral accessibility of the furnace in the neighbourhood of the discharging end and as regards the uniform heating, more particularly in the hotter part of the furnace by the uniform flame which enters
- 10 **10** the hotter part of the furnace at the discharging end and sweeps through the entire furnace being supplemented in the colder part of the furnace, that is towards the charging end, by additional heating means suitably
- 15 **15** consisting in a plurality of burners lying one behind the other in the longitudinal direction of the furnace, which enables flames which gradually increase in heating energy to be introduced into this part of the furnace.
- 20 **20** In a preferred way of carrying out the invention the additional heating is caused to act transversely of the axis of the furnace, in which case it can be regenerative, by the combustion air being preheated, while the
- 25 **25** gas is supplied in regulable quantities to the separate burners increasing towards the discharging end in the manner described above.

The waste gases from this additional heating may then be passed to regenerators

30 **30** which may also receive the waste gases of the single-direction flame sweeping through the entire furnace. If the latter, as explained above, be branched off from a regenerative furnace or flame the waste gases of the additional heating may be introduced as a whole or in part into the regenerators of this regenerative heating system, so that the combustion air required for the additional heating may be taken from these latter regenerators as well. In this case separate regenerators for the additional heating may of course be provided from the regenerators of the regenerative heating system producing the single-direction flame of the furnace.

45 **45** Two constructional examples of the invention are shown in the accompanying drawings, in which

Fig. 1 shows a furnace according to the invention in vertical longitudinal section with regenerative heating for the single-direction flame,

Fig. 2 being a horizontal longitudinal section of Fig. 1.

Fig. 3 shows a second constructional form

55 **55** of furnace according to the invention with ordinary burners for producing the single-direction flame, in vertical longitudinal section,

Fig. 4 being a horizontal longitudinal section of Fig. 3.

Fig. 5 is a horizontal section on the line

55 **55** 5—5 of Fig. 1 showing the gas nozzles for supplying combustible gas to the furnace shown in Figs. 1 and 2.

60 **65** In the constructional form of furnace ac-

cording to the invention shown in Figs. 1 and 2 the air enters through a butterfly valve *a'*, flows alternately through the regenerative chambers *b* and *c* and passes for instance from *b* through the flue *d* into the horizontal passage *e* lying above the end of the furnace. That portion of the air which is to be mixed with the combustible gas to produce the flame to heat the material is drawn by suction from *e* through the suction of the combustible gas flowing out of *f* through the nozzles *h* and is passed into the furnace space proper *g*, forming a flame. The combustible gas is fed under pressure to the separate nozzles *h*. At the other end the passage *e* communicates through the flue *l* with the regenerative chamber *c* so that a portion of the hot combustion air may here flow out of *e* through *l* into the regenerator *c*. For heating the regenerators the flues *d* and *l* are provided with gas supplying means provided with a gas butterfly valve *o* and a gas supply pipe *n* so that each of the regenerators may be heated alternately by a separately formed flame.

According to the invention near the charging end of the furnace a plurality of burners *p* are provided, which as shown in Fig. 2 lie in pairs opposite one another. The burners *p* communicate through vertical passages *q* with the regenerators *b'* and *c'* and are supplied through separate gas pipes *r* with the requisite combustible gas in a regulable manner. The gas and air supply to the burners *p* must also be reversible and for this purpose they are supplied with air which enters through a butterfly valve *a* and flows alternately through the regenerators *b'* and *c'*, each of which is supplied with combustible gas through an independent set of pipes *r*, the arrangement being such that the waste gases pass from the furnace into the regenerator *b'* or *c'* situated opposite that one which for the time being receives combustible gas from its pipes *r* and air through the valve *a*. Any residual waste gases are carried by the air entering from the outside just behind the charging door through the openings and the passages *k* to the chimney.

As the burners *p* receive their combustion air from the regenerators *b'* and *c'* heated by the well-known refining flame and as, on the other hand, the gas can be supplied in an accurately regulable manner by means of the pipes *r*, it follows that the flames entering the furnace from the regenerative burners *p* can be accurately regulated as regards their temperature in such a manner that the temperature of the flames gradually increases from the charging end towards the interior of the furnace.

In Figs. 1 and 2, *s* indicates walls by means of which the regenerators *b* and *c* are separated from the regenerators *b'* and *c'* so that the burners *p* are provided with sep-

arate regenerators. A butterfly valve a' must then be provided for the regenerative heating means of the single-direction flame. The constructional form of the invention shown in Figs. 3 and 4 differs from that just described solely in a different way of producing the single-direction flame which sweeps through the furnace. In this case at the head end of the furnace burners u are arranged in front of the doors t for the ingots, which burners are fed in a known manner with gas, for instance coke oven gas, producer gas or the like, so that a single-direction flame is produced in this instance as well which sweeps through the furnace in its longitudinal direction in opposition to the ingots travelling through the furnace. In the colder parts of the furnace towards the charging end, burners p supplied with gas through pipes r and heated air through passages q are also provided. The waste gases of the single-direction flame pass alternately through the passages q with the waste gases of the additional heating burners p into the regenerators b_2, c_2 , which in this construction extend over the greater part of the length of the furnace and to which air is alternately supplied through the butterfly valve a . The construction and operation of the burners p is the same as that of the corresponding burners p in Figs. 1 and 2.

The regenerators b, c, b_1, c_1 and b_2, c_2 are fitted internally with checkerwork 6.

The flue k at the end of the furnace serves principally for removing the cold air which enters the furnace through the charging door and the residual waste gases.

In the additional heating system of the furnace here shown the successive flames enter the furnace, according to how they are regulated, from one side or the other, so that in consequence the ingots as they move through the furnace at right angles to this flame are heated in their longitudinal direction alternately from one end and from the other. This is, however, only an apparent disadvantage which is compensated to a certain degree by the single-direction flame of the furnace, which coacts with the additional heating system. In the hotter part of the furnace the ingots preheated by the additional heating system are heated through in a completely uniform manner by the single-direction flame which in this part acts with its full energy, so that this initial inequality in heating is of practically no importance.

What I claim is:

1. A reheating furnace for ingots, comprising the combination with a heating chamber having a charging opening at one end and a discharging opening at the other end and means for introducing a combustible mixture into said heating chamber in proximity to said discharging opening, for causing a single-direction flame to sweep through the

heating chamber towards the charging opening, of means for admitting a combustible mixture into said heating chamber in the portion thereof in the neighbourhood of the said charging opening, as and for the purposes set forth. 70

2. A reheating furnace for ingots, comprising the combination with a heating chamber having a charging opening at one end and a discharging opening at the other end and means for introducing a combustible mixture into said heating chamber in proximity to said discharging opening, for causing a single-direction flame to sweep through the heating chamber towards the charging opening, of means arranged in the side of the heating chamber for admitting a combustible mixture into said heating chamber in the portion thereof in the neighbourhood of the said charging opening so as to cause a heating flame to pass across the heating chamber at right angles to the longitudinal axis thereof, as and for the purposes set forth. 75 80 85

3. A reheating furnace for ingots, comprising the combination with a heating chamber having a charging opening at one end and a discharging opening at the other end, a burner arranged at the end of the heating chamber in proximity to said discharging opening for introducing a combustible mixture into said heating chamber and disposed so as to cause a single-direction flame to sweep through the heating chamber towards the charging opening, of burners arranged in the side walls of the heating chamber in the portion thereof near the charging opening, for admitting combustible mixture to said portion of the heating chamber, as and for the purposes set forth. 90 95 100

4. A reheating furnace for ingots as set forth in claim 3, having a pair of regenerative air heating means adapted to be heated by the passage therethrough of products of combustion from the heating chamber, means connected to said regenerative heating means and to the burners arranged near the charging opening for establishing open communication between said burners, the heating chamber and said regenerative heating means, air supply means for admitting air to each of said regenerative air heating means, controlling means interposed in said air supply means for shutting off the air supply to each of said regenerative air heating means alternatively and means for supplying combustible gas to the burners, as and for the purposes set forth. 105 110 115 120

5. A reheating furnace for ingots as set forth in claim 3, having a set of regenerators adapted to be heated by the passage therethrough of products of combustion from the heating chamber, means connected to the burners arranged near the charging opening for establishing open communication between said burners, the heating chamber and said 125 130

regenerators for admitting combustion gases to the regenerators from the heating chamber, and admitting air to said burners from the regenerators, means connected to said regenerators and to the burner situated in proximity to the discharging end of the heating chamber for admitting air to said burner from the regenerators, and means for supplying combustible gas to the burners, as and for the purposes set forth.

In testimony whereof I have signed my name to this specification.

ARTHUR SPRENGER.
